Patent expires December 1, 1963

4 Claims. (Cl. 60—97)

1

For the purpose of lifting loads, for instance, motor cars, lifting members, so called raising platforms, are known, in which said member is supported by a supporting post (column), adapted to be projected hydraulically or pneumatically. If very heavy loads are to be lifted, two or more supporting posts are required for the platform. In lifting devices of this type it is difficult for the platform to be kept in a horizontal position during its movement, especially when the load is not equally divided over the supporting posts.

The invention has for its object to provide a raising platform of the kind referred to having two or more hydraulic or pneumatic supporting posts and in which said difficulty is avoided. The invention consists in this, that a controlling device, adapted automatically to keep the platform in its horizontal position, is provided for each supporting post or for each of the outer posts of more than two aligned posts, each of said devices comprising two valves inserted in series in the liquid conduit connected to the active cylinder space of the corresponding supporting post, of which valves the first, as seen in the direction in which the liquid is supplied, is operated by the difference of pressure existing between two points of said conduit or between a point of said conduit and a point of an air-duct connected to said conduit, and the second is operated in dependency of the position of the platform relative to the corresponding supporting post, in such manner, that during movement of the platform the cross sectional area of the liquid conduit of each post moving too rapidly or too slowly is reduced or increased, respectively. The controlling devices operate so that, if the platform assumes an inclined position, the supply of liquid to or the discharge thereof from the supporting posts is controlled in such a manner that the posts moving too rapidly are checked and the posts moving too slowly are accelerated, until the platform has resumed its horizontal or almost horizontal position.

With a view to ensuring the aforesaid automatic controlling action, the liquid conduit intermediate the two valves may be split into two parallel branches closed, by the first valve, the one during the projection and the other during the retraction of the corresponding post, the cross-sectional area of the opened branch being controlled by the second valve. Preferably, the valves are constituted as cylindrical slide valves, of which the first is exposed to the pressures obtaining at two points of the liquid conduit or the

2

liquid-air conduit and is loaded by springs tending to keep it in its central position, the second being mechanically coupled to the platform, which is hinged to the corresponding supporting post.

In order to ensure a sufficient difference of pressure for the control of the first valve, it is advisable to provide a preferably adjustable throttle in that part of the conduit, in which the difference of pressure is to be produced.

According to the invention, each supporting post may consist of a cylinder and a hollow plunger cooperating therewith, the plunger space communicating with the working cylinder space through a liquid conduit fitted with the controlling device. In that case, the controlling device may be mounted on top of the plunger. If the supporting posts are driven pneumo-hydraulically, the hollow plunger of each post may be partially filled with liquid and connected to a compressed air delivery conduit at a level above that of the liquid. During projection of the supporting post, the liquid is thus urged from the hollow plunger into the working space of the cylinder.

These and other features of the invention will be elucidated hereinafter with reference to the drawing, in which:

Fig. 1 illustrates in diagram a sectional view of a part of a raising platform having a platform supported on two or more supporting posts, of which one only is shown, and

Fig. 2 shows on an enlarged scale a sectional view of the controlling device of the supporting post according to Fig. 1.

Fig. 3 is an elevational view of the upper structure of the raising platform according to Fig. 1, said platform being in an inclined position.

Figs. 3a and 3b show on a larger scale the controlling devices of the supporting post having their parts in the positions corresponding to the inclined position of the platform in accordance with Fig. 3 and during the ascending of said platform.

In the drawing, 1 designates a supporting frame, bridge or platform for lifting loads, for instance a motor car. The platform is supported by and hinged to at least two supporting posts adapted to be hydraulically projected and one of which is shown in Fig. 1. Each of these supporting posts consists of a stationary cylinder and a hollow plunger 3 cooperating therewith. The working space 4 of the cylinder and the plunger space 5 contain liquid and are interconnected by conduits 6 and 7. Inserted between

these conduits is a controlling device 8 arranged in accordance with Fig. 2, said device being mounted on top of the plunger. Connected to the space above the level of the liquid in the plunger is a conduit 9 for compressed air, a branch 10 of which leads to the controlling device.

It will be apparent, that when compressed air is supplied to the plunger, liquid flows from the plunger into the cylinder through conduit 6, the controlling device and conduit 7, and that both the plunger and the platform are lifted. Conversely, when air escapes from the hollow plunger, liquid will return from the cylinder into the plunger and the latter will descend.

The controlling device 8 (Fig. 2) substantially consists of two valves mounted in series intermediate conduits 6 and 7. The conduit 11 connecting the tubes 6 and 7 is split up, intermediate the two valves, into two parallel passages 12 and 13. The first valve, as seen in the direction in which liquid is supplied to the cylinder space 4, consists of two cylindrical slide valves 14, 15 mounted on a common shaft, of which valves one (14) is exposed on its outer face to the pressure of the liquid in the controlling device (i. e. substantially to the pressure of the liquid in the cylinder space 4), and the other confines, by the outer face of its piston, a chamber communicating with the air branch 10 so as to be exposed to the pressure in the plunger. In order to obtain a sufficient difference of pressure between the cylinder space 4 and the plunger space 5 during movement of the plunger, an adjustable throttle 16 is inserted before the first valve in the connecting conduit 11. The cylindrical slide valves 14, 15 are adapted respectively to close and to open the passages 12 and 13. The valves 14, 15 are maintained in central positions by pressure springs 17 and 18 as long as the forces exerted on the piston faces of the valves are equal. The second valve is also constituted as a cylindrical slide valve 19 having a circular row of openings 19a, two of which are shown in Fig. 2. Said valve is connected to the platform by a rod 20 and a lever 21 so as to be actuated whenever the platform alters its position with respect to the plunger. This slide valve controls the cross sectional area of each of the passages 12, 13.

The controlling device operates as follows:

During the raising movement of the platform, liquid is driven, by compressed air, from the plunger through conduit 6, controlling device and conduit 7 to the cylinder space 4. In that case the pressure in the air duct 9 is of course higher than that in the cylinder so that the slide valves 14, 15 of the first valve are lifted, passage 12 is opened and passage 13 is closed (Fig. 2).

Consequently, under these conditions only the passage 12 serves for the control. The cross sectional area of this passage is controlled by the second valve in dependency of the position of the platform. If, during the raising movement, the corresponding supporting post lags behind the other supporting post, the platform will assume the inclined position shown in Fig. 1 and the valve 19 will be forced down so as to fully open the passage 12 (Fig. 2). It will be apparent that the full opening of passage 12 will have effect only when the cross-sectional dimension of all openings 19a together is larger than that of passage 12.

In the other supporting post, however, the valve 19 will be lifted by the inclined position of the platform, so as to close passage 12. The

result of this controlling action is that the supporting post, which is lagging behind, is supplied with an appreciable amount of liquid, whereas hardly any liquid is supplied to the supporting post that is raised too rapidly. Consequently, the platform resumes its horizontal position.

In Figs. 3, 3a and 3b is illustrated what happens when in the above mentioned case the platform is ascending in an inclined position. Assuming the left hand supporting post to lag behind the right hand supporting post, slide valve 19 of the first mentioned supporting post will be forced down so as to open passage 12 to a degree corresponding with the inclination of the platform (Fig. 3a), while slide valve 19 of the second supporting post will be drawn upwards so as to close passage 12 to a greater or less extent (Fig. 3b). The result thereof is that the supply of liquids to the lagging supporting post is increased, while that of the other supporting post is decreased.

During the descending movement, the reverse takes place. In that case, the pressure in the cylinder 2 exceeds that in the airduct 9, so that the valves 14, 15 are forced down, passage 13 is opened and passage 12 closed. The slide valve 19 of the second valve then controls the cross sectional area of passage 13, in such manner that, if the descending movement is too rapid or too slow, the discharge of liquid from the cylinder is reduced or fully checked, or increased, respectively.

When the platform is ascending or descending in an exactly horizontal position the valves 19 of the two controlling devices 8 are placed in equal positions relative to the corresponding passages 12 and leave the latter half opened.

In order that, in case of rupture of a conduit, for instance of the airduct 9, the corresponding supporting post would not descend, the controlling device comprises a check valve 22 maintained in its open position by an adjustable spring 23, but closing automatically if the pressure in conduit 6 is lower than that in conduit 7 and the difference of pressure exceeds a certain value. This check valve also restricts the velocity at which the platform can descend.

When the platform is carried by three or four supporting posts, a very accurate control is obtained if the levers controlling the valves 19 point to the centre of the triangle or the quadrangle connecting the posts. The connection between the platform and the supporting posts and that between the platform and the control levers of the controlling devices should then be constituted by ball or universal joints.

When the platform is carried by three aligned supporting posts, the control device of the central post may be omitted. In that case, however, it is necessary that the cross sectional area of the non-controlled connecting conduit of the central supporting post substantially equals the maximum cross sectional area of the connecting conduit of each of the other supporting posts.

It is not necessary that each control device be mounted on its individual post. For instance, two control devices forming a single unit, may be mounted on one supporting post.

Instead of compressed air, liquid may be supplied or discharged through conduit 9, so that instead of a pneumo-hydraulic system a purely hydraulic system is obtained.

The throttle 16 can be omitted when the cross sectional area of conduit 6 is restricted. The pro-

vision of a throttle has, however, the advantage that said member can be easily adjusted.

Attention is drawn to the fact that the springs 17, 18 for returning the slide valves 14, 15 to their central positions may be omitted. In that case, the terminal positions of the valves, in which one of the passages 12, 13 is open and the other closed, should be defined by abutments.

What I claim is:

1. A raising platform or lift, particularly for lifting a load such as a motor vehicle, comprising at least two supporting posts, a reservoir adapted to contain fluid under pressure, and for each of said posts a cylinder and a piston adapted to move said post hydraulically, a pressure fluid conduit connecting said cylinder to said reservoir and two valves constituting a device for controlling the pressure fluid within said conduit and for maintaining the platform automatically in a horizontal position, one of said valves being operated by the difference of pressure obtaining at two points in the pressure fluid system, the other valve being operated in dependency of the position of the platform relative to the corresponding supporting post, and the part of said fluid conduit intermediate the two valves including two branches, one of which is closed during upward movement and the other during downward movement of said post by the first mentioned valve, the cross-sectional area of the other branch being controlled by the second valve.

2. A raising platform or lift as claimed in claim 1 in which the piston of each of said supporting posts is constituted as a hollow plunger, the plunger space communicating with the working space of the corresponding cylinder through a liquid conduit, in which the controlling device is inserted.

3. A raising platform according to claim 1 in which the piston of each of said supporting posts is constituted as a hollow plunger, the plunger space communicating with the working space of the corresponding cylinder through a liquid conduit, in which the controlling device, being mounted on top of the plunger of the corresponding post, is inserted.

4. A raising platform according to claim 1 in which the piston of each of said supporting posts is constituted as a hollow plunger, the plunger space being partially filled with liquid and connected, at a level above that of the liquid, to a compressed air conduit, the working space of the corresponding cylinder communicating with said plunger space through a liquid conduit, in which said controlling device, being mounted on top of the plunger of the corresponding post, is inserted, and said first mentioned valve being exposed on one side to the pressure in a point of the liquid conduit, on the other side to the pressure in a point of the air-duct.
